(57) **CLAIM**

The ornamental design for a handle for a carpet seam roller as shown and described.

DESCRIPTION

FIG. 1 is a top plan view of a handle for carpet seam roller; FIG. 2 is left side elevation view thereof; FIG. 3 is bottom plan view thereof; FIG. 4 is a left-end elevation view thereof; FIG. 5 is a right-end elevation view thereof; FIG. 6 is a right side elevation view thereof; FIG. 7 is a perspective view thereof taken from the front left side and illustrating the environment (roller and yoke) in broken lines; and, FIG. 8 is another perspective view thereof taken from the rear left side and illustrating the environment (roller and yoke) in broken lines. The broken lines illustrate the environment and form no part of the claimed design.

1 Claim, 3 Drawing Sheets
